HOUSEHOLD MIXER

John R. Gomersall, deceased, late of Elgin, Ill., by Florence Judith Gomersall, executrix, Elgin, Ill., Murray Ireland, Elgin, and Philip E. Willman, St. Charles, Ill., assignors to McGraw-Edison Company, Milwaukee, Wis., a corporation of Delaware

Filed Aug. 1, 1960, Ser. No. 46,845

3 Claims. (Cl. 259—1)

This invention relates to electric appliances such as household mixers and the like.

Electric food mixers are generally of three types; those consisting merely of a mixer head, commonly referred to as portable mixers; those which consist of a mixer head fixedly attached to a mixer stand; and a combination of the first two which has a mixer head releasably supported on a mixer stand so that the head may be used with the stand or as a portable mixer. Regardless of the type of mixer, it is recognized that some means of mechanically ejecting the beaters from the mixer head is desirable. Some attempts have been made to supply such a beater release mechanism, but these attempts have all possessed the undesirable feature that many times the mechanical ejector is actuated while the beaters are being driven. This, in addition to possibly damaging the beaters, is messy and presents quite a vexatious problem to the housewife. One proposed solution to this problem was to position the beater release actuating button away from the areas normally contacted by the housewife when the mixer is in use. However, the possibility of accidental ejection is still present regardless of where the beater release actuating button is positioned.

Also, common practice in the use of a mixer is to disassemble it when not in use, e.g., remove the beaters and electric cord. The problem then becomes one of safe and convenient storage. For example, the beaters are generally stored in a drawer where they can be damaged and, further, when the beaters and cord are separated from the mixer they may quite easily be lost.

This invention contemplates providing a household mixer including beater release mechanism having associated therewith means for selectively preventing actuation of the beater release mechanism, which means is in turn controlled by the control means for the mixer motor so that the beater release mechanism cannot be actuated while the mixer motor is running. It is also contemplated to provide a mixer stand which will accommodate the disassembled parts of the mixer for safe and convenient storage.

Accordingly, it is an object of this invention to provide a household mixer having a beater release mechanism which cannot be operated while the mixer motor is running.

Another object of this invention is to provide a beater release mechanism which is associated with and controlled by control means for the mixer motor so that the beater release cannot be actuated while the motor is running.

A further object of this invention is to provide safe and convenient storage for a mixer.

A still further object of this invention is to provide a mixer stand which will accommodate the disassembled

2

parts of the mixer for ready storage and is itself readily stored.

These and other objects and advantages of this invention will become more readily apparent from a reading of the following description in connection with the drawings in which:

FIG. 1 is a side elevation of an electric household mixer embodying this invention;

FIG. 2 is an enlarged side elevation of the forward portion of the mixer head with the outer housing removed to expose the beater release mechanism;

FIG. 3 is a front elevation of only the beater release mechanism of FIG. 2;

FIG. 4 is a bottom plan view of the front portion of the mixer head with the bottom cover plate removed;

FIG. 5 is an enlarged cross sectional view taken along lines 5—5 of FIG. 3;

FIG. 6 is an enlarged cross sectional view taken along lines 6—6 of FIG. 3;

FIG. 7 is a cross sectional view of the mixer stand taken along a vertical plane through the center of the stand;

FIG. 8 is a view of the upper end only of the support arm of the mixer stand;

FIG. 9 is a cross sectional view taken along lines 9—9 of FIG. 7;

FIG. 10 is a view, in perspective, of a portion of the mixer stand.

In the drawings, an electric household mixer 1 is illustrated as including a head 3 and stand 5. The head 3 includes suitable driving means (not shown) such as an electric motor connected to and rotatably driving a pair of beaters 7. The beaters 7 are releasably supported in the head 3 in a manner to be described more particularly hereinafter.

The stand 5 includes a base portion 9 and support means in the form of a collapsible arm 11 the upper end of which releasably supports the mixer head 3. Base portion 9 also includes a rotatable disk 13 for supporting a mixing bowl (not shown) below the beaters 7.

Reference will now be made to FIGS. 2—6 for a more complete description of the beater release mechanism and the means provided for preventing actuation of the beater release mechanism while the mixer motor is running.

A shaft 15 extends from the mixer motor to a gear box 17. Extending from the bottom of the gear box 17 are two stub shafts 19, each disposed in a post 21. Disposed at the lower end of and integral with each of the stub shafts 19 is an axially slotted beater engaging portion 23. Beaters 7 are each provided with radially extending projections 25 which fit into the axial slots of the beater engaging portion 23 to releasably support the beaters in the mixer head and connect the beaters to the stub shafts 19 so that they can be rotatably driven by the mixer motor.

A preferred form of beater release mechanism in accordance with this invention includes an ejector plate 27 pivotally connected in the mixer head 3 adjacent the beaters 7 and movable into engagement with the beaters to eject them from the mixer head. Ejector plate 27 includes a generally flat body portion 29 and a pair of side arms 31. The ends 33 of the arms 31 are turned inwardly and are each provided with a notch 35. The notched ends 33 cooperate with recesses 37 in rib por-

tions 39 of the mixer head 3 to provide a pivot point about which the ejector plate 27 is movable.

A plate 41, preferably stainless steel, closes the underside of the forward portion of the mixer head 3 and is fixed in position by means of a mounting bracket 43 and screw 45. The cover plate 41 includes an aperture 47 through which an arcuate beater engaging arm 49, which is integral with the body portion 29 of the ejector plate 27, passes upon actuation of the beater release mechanism. A spring 51 extends between an apertured lip 53 of the mounting bracket 43 and an apertured arm 55 of the ejector plate 27 and normally urges the ejector plate 27 upwardly and out of the aperture 47. Each of the beaters 7 is provided with a generally circular flange 57 which, upon actuation of the beater release mechanism, is engaged by the arcuate arm 49 of the ejector plate 27 so that the beaters can be ejected from the mixer head.

Means for moving the ejector plate 27 into and out of engagement with the beaters 7 is provided and includes a beater release button 59 and an actuating lever 61. The beater release button 59 extends through the upper portion of the mixer head 3 and is rotatably mounted on a support plate 63. The support plate 63 is preferably metallic to give adequate support and is held in a vertical position by means of a pair of upstanding grooved arms 64 which are attached to the gear box 17. The rotatable mounting of the beater release button 59 is accomplished by means of a headed pin 65. Also rotatably mounted on the pin 65 is a link 67. As can be seen in FIG. 2, upon rotation of the beater release button 59 the link 67 will also be displaced about the pin 65.

The actuating lever 61 is provided with shouldered projections 71 and 69 at its upper and lower ends respectively. The projection 69 fits into an aperture 73 in the ejector plate 27, and the projection 71 engages the link 67. The actuating lever 61 then operatively connects the beater release button 59 to the ejector plate 27 and transfers the motion of the beater release button 59 to the ejector plate 27 for beater ejection.

Mechanical ejection of the beater 7 is then accomplished by rotating the beater release button 59 to displace the bracket 67, which bracket in turn displaces the actuating lever 61. Displacement of the actuating lever 61 produces movement of the ejector plate 27 and extension of the arcuate beater engaging arm 49 through the aperture 47 and into engagement with the flanges 57. Continued movement of the beater release button 59 forces the projections 25 of the beaters 7 out of engagement with stub shafts 19 to thereby release the beaters from the head 3.

To limit the travel of the beater release button 59, the button is provided with a raised portion 75 which, upon rotation of the button 59, travels in an arcuate slot 77 in the upper end of the support plate 63. The opposed ends of the slot 77 provide stops for the beater release button in both directions of rotation and prevent overtravel of the beater release button 59 in either direction.

Stop means is provided for selectively locking the beater release mechanism against motion and freeing the beater release mechanism for movement to eject the beaters from the mixer head. The stop means preferably includes a lever 79 rotatably connected to the support plate 63 by means of a headed pin 81 and a projection 83 attached to the actuating lever 61. The upper end of the lever 79 is bent at right angles to the lever 79 and is disposed in an aperture 85 in the support plate 63 so as to have a portion 87 extending on one side of the support plate 63 and a portion 89 extending on the opposite side of the support plate 63. A coil spring 91 is disposed on the pin 81 and engages suitable tabs 93 and 95 of the support plate 63 and the lever 79 respectively. The spring 91 normally urges the lever 79 into the dot-dash position shown in FIG. 5, in which position the projection 87 engages the projection 83, of the

actuating lever 61, thereby locking the beater release mechanism against motion. When the lever 79 is in the full line position illustrated in FIG. 5 the beater release mechanism is free to move for ejection of the beaters from the mixer head.

To insure that the beater release mechanism cannot be actuated while the mixer motor is running, the stop means just described is associated with and controlled by the same means which is provided for energizing and deenergizing the motor of the mixer.

The mixer motor control means preferably takes the form of switch means 97 and in order to facilitate the description of the cooperation between the motor control means and the stop for the beater release mechanism a brief description of switch means 97 will be made.

The switch means 97 includes a switch actuating button 99 rotatably mounted on a suitable fiber electrically insulating support plate 101. The support plate 101 is held in a vertical position by means of upstanding grooved arms 103 attached to the gear box 17 and identical to the mounting arms 64. The switch actuating button 99 is rotatably connected to the support plate 101 by means of a headed pin 105. Also mounted on the headed pin 105 and fixed to and rotatable with the switch actuating button 99 is a movable electric contact arm 107. The electrical contact arm 107 is movable between an off position and preferably a plurality of on positions. Referring to FIG. 6, in the position as illustrated the electrical contact arm 107 is in the off position and by counterclockwise rotation of the switch actuating button 99 the contact arm 107 can be moved into engagement with any one of three stationary electrical contacts 109, 111, and 113. The stationary electrical contacts 109, 111 and 113 correspond respectively to low, medium and high mixer motor speeds.

To positively index the movable contact arm 107 in any one of its four positions, namely off, low, medium and high, indexing means in the form of apertures 115 in the support plate 101 and a second spring arm 117 having an indentation 119 in the end thereof is provided. The second spring arm 117 rotates with the movable contact 107 and the recess 119 is complementary to the apertures 115. Thus as the switch actuating button 99 is rotated about the pin 105 the apertures 115 and the recess 119 cooperate to positively index and lock the movable contact arm 107 with respect to any one of the stationary contacts.

Electrical energy is commonly supplied to the mixer motor by means of a detachable electric cord (not shown) and the switch means 97 is placed in and is operative to selectively complete and open the electric circuit to the motor. More particularly, an electrically conductive tab 121 is provided and is adapted to receive one of the line leads. The tab 121 is electrically connected to the movable contact arm 107 which then transmits electrical energy to any one of the three stationary contacts. The stationary contacts are in turn each connected to one side of the mixer motor.

To prevent overtravel of the switch actuating button 99, stop means identical to the stop means provided to eliminate overtravel of the beater release button 59 is provided in the form of a projection 123 on the switch actuating button which travels in an open arcuate slot 125 in the support plate 101.

Returning now to the cooperation between the switch means 97 and the stop for the beater release mechanism, the switch actuating button 99 is provided with a laterally extending arm 127 which is so disposed as to be engageable with the projection 89 of the lever 79. As illustrated in FIGS. 5 and 6, when the switch means 97 is in the off position the arm 127 is in engagement with projection 89 and holds the lever 79 in the full line position and away from the projection 83 on the actuating lever 61 so that the beater release mechanism is then free for movement. As the movable contact arm 107 is moved to the station-

ary contact 109 to energize the mixer motor the laterally extending arm 127 is moved to the dotted position shown in FIG. 5, thereby releasing the lever 79 which under the influence of the spring 91 is moved to the dotted position in FIG. 5 and engages the projection 83 of the switch actuating lever 61 to lock the beater mechanism against movement. As the movable contact arm 107 is actuated through the remaining switch positions, namely medium and high speeds, the lever 79 remains in the dot-dash position of FIG. 5 and continues to lock the beater release mechanism against movement. Only upon return of the movable contact arm 107 to the off position, and re-engagement of the arm 127 with the projection 89 and displacement of the lever 79 to the full line position and out of engagement with the projection 83, can the beater release mechanism be actuated. It can thus be seen that a positive stop is provided which locks the beater release mechanism against movement whenever the mixer motor is energized and the beaters are being driven so that the beaters cannot be ejected.

Reference will now be made to FIGS. 7-10 for a more specific description of the novel stand 5 of this invention. The stand 5 includes a collapsible support arm 11 pivotally connected at one end to the base portion 9 of the stand 5 by means of a pin 131 and a bracket 133. The arm 11 can be pivoted between a substantially upright operating position, shown in full lines, and a collapsed storage position, shown by the dot-dash lines. When the support arm 11 is in the collapsed position it is compactly nested with the base portion 9 and the stand 5 is readily adapted for easy storage.

Locking means 135 is provided for holding the support arm 11 in its upright operating position, and preferably includes an elongated lever 137 pivotally mounted on the bracket 133 by a pin 139. The lever 137 includes an L-shaped slot 141 which engages a pin 143 that is fixed to the support arm 11. When the pin 143 is engaged in the shorter leg of the L-shaped slot 141 the support arm 11 is locked in the upright position. To insure continuous engagement of the pin 143 in the shorter leg of the slot 141 a coil spring 145 is provided on the pin 139 and suitably engages the bracket 133 and the slot 141 to urge the lever 137 into engagement with the pin 143. The L-shaped slot 141 serves the further function of providing a guide in which the pin 143 moves as the support arm 11 is lowered to its collapsed position.

The upper end of the support arm 11 is provided with hinge means 147 which releasably supports the mixer head 3. The hinge means 147 is operative between two positions, one wherein the mixer head is disposed in operating position and a second position wherein the mixer head is pivoted to swing the beater blades free of the mixing bowl so that the mixing bowl is easily removed. The hinge means 147 includes a rotatable plate 149 supported on a pin 151 which is fixed to the support 11 by means of a bracket 153. The plate 149 has an upwardly extending arm 155 which engages the mixer head 3 as is illustrated in FIG. 1.

Means for indexing the hinge means 147 in either one of its two positions is provided and preferably takes the form of a ball 157 and a pair of notches 159 complementary to ball 157. The ball 157 is positioned in a bracket 161 and is urged into engagement with the notches 159 by a spring 163. FIGURES 7 and 8 illustrate the hinge means in both of its extreme positions.

To insure positive positioning of the mixer head, the rotatable plate 149 is provided with a first shoulder 165 disposed to engage the support arm 11 when the mixer head 3 is in its operating position, which is illustrated in FIG. 7. A second shoulder 167 is provided and also engages the support arm 11, as illustrated in FIG. 8, when the mixer head 3 is pivoted to the non-operating position to clear the beaters 7 from the mixer bowl. The weight of the mixer head holds the shoulders 165 and 167 in engagement with the support arm 11.

The base portion 9 is generally hollow and preferably includes two partitions 169 and 171 which divide the interior of the base portion 9 into a plurality of open-ended separate compartments 173, 175, and 177. Means in the form of a door 179 hingedly connected to the open end of the base portion 9 is provided for normally closing the open-end of base portion 9. The compartments 173, 175 and 177 accommodate the beaters 7 and the electrical cord 181, as is illustrated in FIG. 10.

When the mixer is not in use the disassembled parts, such as the beaters and the electrical cord, are stored within the base portion 9. The support arm 11 is collapsed and the stand 5 can be easily stored and will occupy a minimum of space. By providing the self storing stand 5, the disassembled parts of the mixer are kept together and are stored in a manner which prevents damage to those parts.

The description of our invention in relation to a particular preferred embodiment thereof is intended for illustrative purposes only; and it is intended in the appended claims to cover all modifications and embodiments of our invention as fall within the true spirit and scope thereof.

What we claim is:

1. In a mixer head including beater means, motor means for driving said beater means, and control means for selectively energizing and de-energizing said motor means; the combination with said beater means of an ejector plate pivotally mounted for movement into engagement with said beater means to eject said beater means from said head portion; a manually operable button independent and horizontally displaced from said control means, a lever connecting said button to said ejector plate for moving said ejector plate into beater ejecting engagement with said beater means upon actuation of said button; a stop member pivotally mounted adjacent said lever and pivotable into and out of a lever engaging position to respectively lock said lever against movement and free said lever for movement; and biasing means urging said stop member toward said lever engaging position, said control means engaging and moving said stop member out of lever engaging position when said control means is disposed in a position wherein said motor means is de-energized.

2. In a mixer head including beater means, motor means for driving said beater means, and control means for selectively energizing and de-energizing said motor means, the combination with said beater means of ejector means pivotally connected in said head adjacent to said beater means for movement into engagement with said beater means to eject said beater means from said head; actuating means independent of said control means for moving said ejector means into beater ejecting engagement with said beater means; stop means associated with said actuating means for movement into and out of an actuating means engaging position to respectively lock said actuating means against movement and free said actuating means for movement; and biasing means urging said stop means toward said actuating means engaging position, said control means engaging said stop means and moving said stop means out of said actuating means engaging position when said motor means is de-energized.

3. In a mixer head including beater means, motor means for driving said beater means, and control means for selectively energizing and de-energizing said motor means; release means independent of said control means and movable into and out of engagement with said beater means for ejecting said beater means from said head; stop means movable between first and second positions respectively into and out of a release means engaging position respectively to restrain said beater means against beater engaging motion and to free said release means for beater ejecting motion and biasing means urging said stop means toward one of said positions, said stop means being engageable by said control means for movement to the other of said positions, said biasing means and control

means cooperating to dispose said stop means in said first position when said motor means is energized and in said second position only when said motor means is de-energized.
